UNITED STATES PATENT OFFICE.

JEAN CHARLES MATTER, OF MÜLHAUSEN, GERMANY.

MACHINE FOR SIFTING COLORS.

SPECIFICATION forming part of Letters Patent No. 295,783, dated March 25, 1884.

Application filed October 22, 1883. (No model.) Patented in England September 25, 1883, No. 4,570, and in France October 8, 1883, No. 145,527.

To all whom it may concern:

Be it known that I, JEAN CHARLES MATTER, of Mülhausen, Germany, have invented an Improved Machine for Sifting Colors, of which

5 the following is a specification.

The machine for sifting colors forming the object of this invention is chiefly designed to effect, automatically, the operation of sifting colors, which up to the present time has been 10 performed by hand. The sifting by hand being a long and accordingly expensive process, requiring tedious and in most cases unwholesome work, it has been for a length of time the aim of many attempts to substitute for the same 15 the action of machinery, which is well known to be more efficient than hand-work. Yet, while the principal devices hitherto used for the purpose—such as the apparatus for sifting *in vacuo* and the press—have attained 20 some progress with regard to economy, they are far from proving advantageous respecting the perfection of the work obtained. The sifting *in vacuo*, as well as by means of the piston of a press, allows, in fact, of the materials passing through the sieve about in the 25 same state as before the operation. The grains, lumps, and other particles thereof are not crushed as thoroughly as they are through the action of the brush moved by hand; they remain in the sieve, and the work done is incomplete. On the other hand, the operation effected by hand, expensive as it is in itself, becomes still more so by reason of the necessity 30 of a frequent replacement of the sieve, which soon gets unserviceable under the uneven action of the strokes of the brushes produced by the operative. Now, the machine embodying my invention presents the combined advantages of economy such as is realized by automatical work, and of the perfection obtained 35 by manual labor, preventing, however, the drawbacks inherent to all the methods now in use, such as the sifting *in vacuo* or by means of a piston. It moreover materially lessens 40 the wear and injury of the sieves by reason of the uniformity and elasticity of the pressure exerted upon the sieve by the brush.

45 My invention substantially consists in the construction of the machine, as hereinafter described, and more particularly recited in the claims.

The construction and operation of this machine will be clearly understood on reference being had to the accompanying drawings, in which—

55

Figure 1 is an elevation, and Fig. 2 a plan, of my improved machine.

I generally construct the same double—that is to say, that one driving-shaft operates two sieves at a time.

60

In the drawings, A represents the driving-shaft, provided with fast and loose pulleys P P', by means of which and bevel-wheels a a' revolution is communicated to two vertical shafts, B B'. At the end of each of these 65 shafts I fix a crank, C or C'. Onto these cranks a connecting-rod, D, is placed, said cranks communicating to the ends of the rod a circular motion corresponding to the circular movement of the crank-pins.

70

E E' represent spindles, each carrying a brush at its lower end and extending upward through a ring, c or c', on the respective ends of the connecting-rod. The upper ends of the spindles E E' are swiveled, respectively, to 75 rods G G', and these rods are arranged to swing in vertical planes from the centers b b'. The connecting-rod, therefore, under the movement imparted to it from the cranks, imparts to the brushes a revolving swinging movement. The counter-weights H H' are applied to the rods G G', by which the pressure of the brushes upon the sieves may be regulated. The sieves each rest upon a toothed ring, I, 80 which is arranged for rotation around its own axis. On each of the vertical shafts is a pinion, d', which, through an intermediate pinion, d, communicates rotation to the ring and the sieve thereon, but in the opposite direction to the rotation imparted to the brush.

85

This construction of machine presents the advantages hereinbefore specified—to wit, continuity and regularity of work under uniform pressure.

I have illustrated the sieves as a pair, and 90 this arrangement I prefer; but one of the sieves may be omitted.

What I claim is—

1. The combination of a sieve arranged for rotation in a horizontal plane, a spindle, E, 95 carrying a brush within the sieve, the said spindle being suitably swiveled, and mechan-

ism, substantially such as described, for communicating rotation to the sieve in one direction and rotation to the brush in the opposite direction, substantially as described.

5 2. The combination of two sieves arranged for rotation in a horizontal plane, mechanism, substantially such as described, for imparting such rotation to said sieves, the two cranks C C', the rod D, connecting said cranks and 10 extending over the sieves, and carrying at its extreme ends the rings c c', the brush-spindles

E E', carrying brushes at their lower ends, extending up through said rings c c', and suspended at their upper ends by swivel-joints, substantially as described.

15 In testimony whereof I have signed my name to this specification before two subscribing witnesses.

JEAN CHARLES MATTER.
